UNITED STATES PATENT OFFICE.

JOHN RUCH AND JOHN RUCH, JR., OF PHILADELPHIA, PENNSYLVANIA.

MOTHPROOFING CURLLED HAIR.

SPECIFICATION forming part of Letters Patent No. 369,739, dated September 13, 1887.

Application filed May 21, 1886. Serial No. 202,906. (No specimens.)

To all whom it may concern:

Be it known that we, JOHN RUCH and JOHN RUCH, Jr., both citizens of the United States, residing in Philadelphia, Pennsylvania, have 5 invented certain Improvements in Mothproofing Curled Hair, &c., of which the following is a specification.

The object of our invention is to effect the destruction and prevent the breeding of moths 10 and other insects in curled hair and like materials used in upholstery, and this object we attain in the manner hereinafter set forth.

We have found by experiment that products arising from the distillation of wood or woody 15 fibers have a destructive influence upon the worms or larvae of moths and upon other insects, and that when curled hair and like upholstery materials are treated with such distillates in the manner hereinafter set forth said 20 materials are rendered proof against the ravages of these insects.

The distillates which we prefer to use are creosote and pyroligneous acid; but other wood distillates having similar properties may 25 be employed, if desired.

In carrying out our invention we take the creosote or pyroligneous acid, or a combination of the two, and subject the curled hair or other material which is to be protected to the 30 direct action of the destructive and preventive agent. This may be done by steeping, dipping, or boiling the material in the distill-

ate, or in a solution of the same; or the liquid may be sprayed over the material or applied by means of a brush or swab, or in such other ways as circumstances may suggest as the most appropriate, the treated material being then dried.

Distillates of the character specified have the quality of so thoroughly impregnating the 40 fibers that when the latter are dried the protecting agent will be combined therewith in the form of a fixed deposit.

Curved hair and like upholstery materials treated in this way are thus permanently unfitted as food for the worms or larvae of moths and other insects, and hence are rendered 45 proof against the ravages of such insects.

We therefore claim as our invention—

The mode herein described of mothproofing 50 curled hair and like upholstery material, said mode consisting in impregnating the material with creosote or its specified equivalent and then drying the material, so as to leave the protecting agent permanently combined therewith, all substantially as specified.

In testimony whereof we have signed our names to this specification in the presence of two subscribing witnesses.

JOHN RUCH.

JOHN RUCH, JR.
